UNITED STATES PATENT OFFICE

2,634,480

STRAP BUCKLE

Fredric A. Ray, Reseda, Calif.

Application July 24, 1950, Serial No. 175,551

1 Claim. (Cl. 24—180)

1

My invention relates to buckles of the hinged box type and which are associated with straps used for various purposes; for instance, belts, stirrup leather straps and the like, and the principal objects of my invention are, to provide a simple, compact and highly effective buckle comprising two parts hinged to each other, with one part carrying one or more fixed tongues or studs which, when the buckle is closed, engages in apertures in the other part so as to provide an exceptionally strong and at the same time a readily releasable connection between two straps or the end portions of a single strap.

A further object of my invention is to provide a keeper which combines with the improved buckle in holding the connected straps in compact connected position, and which keeper is formed separately from the buckle, in order that it may be readily adjusted toward or away from same to meet different conditions.

With the foregoing and other objects in view, my invention consists in certain novel features of construction and arrangement of parts which will be hereinafter more fully described and claimed, and illustrated in the accompanying drawing, in which:

Fig. 1 is a front elevational view of my improved buckle and keeper in position upon a strap.

Figs. 2 and 3 are perspective views of the two parts of my improved buckle.

Fig. 4 is a perspective view of the keeper.

Fig. 5 is an edge view of the connected portions of a strap with my improved buckle and keeper in position thereupon.

Fig. 6 is a vertical section taken on the line 6—6 of Fig. 1.

Fig. 7 is a horizontal section taken on the line 7—7 of Fig. 1.

Fig. 8 is a horizontal section taken on the line 8—8 of Fig. 1.

Fig. 9 is a horizontal section similar to Fig. 8, and showing a modified form of the keeper.

Referring by numerals to the accompanying drawing, which illustrates a preferred embodiment of my invention, 10 and 11 designate respectively the over and underlying portions of a strap such as a trousers' belt or the stirrup leather of a saddle, and secured, preferably by rivets 12, to the inner or under face of strap portion 11 at the end thereof, is a plate 13, from the end of which project at right angles, ears 14, provided in their upper portions with apertures 15. The upper edge of plate 13 occupies a horizontal plane between ears 14, just below the apertures 15 therein and formed through said

plate just below said upper edge are apertures 16.

A plate 17 lies across the front face of strap portion 10 and projecting at right angles from the ends of said plate are ears 18, provided with apertures 19 for the reception of hinge pins 20, which also pass through the apertures 15 in ears 14, thus hinging buckle part 17 to part 13.

Seated in the lower portion of plate 17 are studs or pins 21, which function as buckle tongues and when the buckle is closed on straps or strap parts, as seen in Figs. 6 and 7, these studs pass through the apertures 16 in plate 13, thus reinforcing the buckle against any tendency of the parts thereof to separate due to abnormal strains impressed lengthwise on the strap or straps.

Studs 21 pass through apertures 22 spaced longitudinally in strap 10, and when the buckle is closed said studs pass directly above the upper end of strap 11 (see Fig. 6).

20 I have shown the apertures 22 arranged in pairs; but, in narrow straps, for instance, trousers' belts, only a single row of such apertures and a single stud or tongue 21 is required.

To open the buckle for release and/or adjustment of strap portion 10, it is only necessary to swing plate 17 carrying studs 21 outwardly and upwardly from plate 13, thus withdrawing studs on tongues 21 from the apertures 19 in strap 10 (see Fig. 5).

25 The lowered upper edge of plate 13 enables the latter to freely swing upward and outward when the buckle is opened.

The keeper for the end portion of the strap beyond the buckle comprises a narrow rectangular loop 23, adapted to pass around straps 10 and 11 and projecting from the inner face of one of the side walls of said loop are studs 25, which engage in the apertures 22. Thus, the keeper may be readily adjusted on strap 11 so as to maintain the portion of strap 10, beyond the buckle, against said strap 11.

30 In Fig. 9 I have shown a keeper or loop 26 with a single stud 27 designed for use on straps having the stud-receiving apertures 22 formed in a single row.

45 Thus it will be seen that I have provided a strap buckle and keeper which is simple and compact in structure, inexpensive of manufacture, capable of being readily opened, closed and adjusted and very effective in performing the functions for which it is intended.

The two studs 21 rigidly seated in plate 17, passing at right angles through strap 10 and fitting snugly in the apertures 16 in plate 13, 50 provide a very strong and rigid two point con-

nection and bearing between the two parts of the buckle and strap, or strap portion 10, thus adding materially to the service efficiency of the buckle.

Minor changes in the size, form and construction of the various parts of my improved strap buckle and keeper may be made and substituted for those herein shown and described, without departing from the spirit of my invention, the scope of which is set forth in the appended claim. 5

I claim as my invention:

In a strap buckle, a plate, ears projecting at right angles from the ends of said plate, said ears being extended beyond said plate and said extensions being perforated, a strap permanently secured to the lower portion of the inner face of said plate, there being apertures formed in said plate just above the end of said strap, a second plate, ears on the ends thereof, which ears extend beyond the upper edge of said second mentioned plate, said ears being perforated, hinge pins seated in the apertures in said pairs of ears, 10 15 20

and pins projecting from said second mentioned plate for engagement in the apertures in said first mentioned plate just above said strap when said plates are closed.

FREDRIC A. RAY.
